UNITED STATES PATENT OFFICE.

ARTHUR F. HETHERINGTON, OF NEW YORK, N. Y.

SAFETY COUPLING-RELEASE SYSTEM FOR RAILWAY-TRAINS.

1,141,393.

Specification of Letters Patent.

Patented June 1, 1915.

Application filed December 4, 1909. Serial No. 531,367.

To all whom it may concern:

Be it known that I, ARTHUR F. HETHERINGTON, a citizen of the United States, and a resident of the borough of Manhattan, 5 city, county, and State of New York, have invented certain new and useful Improvements in Safety Coupling-Release Systems for Railway-Trains, of which the following is a specification, accompanied by drawings.

10 This invention relates to improvements in safety coupling release systems for railway trains and the object of the invention is to provide means for insuring the release of all the couplings of a train in case of derailment of the engine. By this means the engine may become derailed, but will be prevented from causing the derailment of the remainder of the train. Furthermore, the derailment of one or more cars will not cause 15 20 25

the derailment of the remainder of the cars, because all the cars will be automatically uncoupled.

To these ends the invention in one of its preferred forms is described and claimed in 25 this specification and shown in the accompanying drawings, in which—

Figure 1 is a side elevation partly broken away of a portion of a train equipped with devices for carrying out this system; Fig. 2 30 is an enlarged detail side elevation partly in section showing the contact shoe adapted to bear upon the rails; Fig. 3 is an enlarged diagrammatic view partly in longitudinal section and partly broken away, showing 35 the details of the system; Fig. 4 is an enlarged detail plan view of a portion of the uncoupling device; Fig. 5 is a detail plan view partly broken away of a modification 40 of the uncoupling device; and Fig. 6 is a side elevation of Fig. 5.

Referring to the drawings, A represents the engine, B the tender and C one of the cars of which there may be as many as desired in a train and all connected to be automatically uncoupled in accordance with this system if the engine is derailed. A shoe D is preferably supported from the frame of the engine and bears upon one rail, and circuits and devices are provided upon the train, so devised that the couplings E and coupling chains F are all released in case the engine and with it the shoe D leaves the rails. 45 50

In Fig. 3 the circuits devised are shown in detail, in which a, b represent the con-

ductors of an electric circuit extending 55 throughout the train and energized from any suitable source of electricity, as a storage battery G, which may be contained in the casing H shown for convenience as carried by the tender B. The circuit a, b of the 60 storage battery G is normally open, but is adapted to be automatically closed when the shoe D leaves the rails.

The shoe D is carried by the telescopic guide rods J attached at K to the bed of the 65 engine. Inside the hollow portions L of the rods are compression springs O which normally tend to force the shoe D downwardly. The shoe is provided with the central stem P having the contacts Q normally separated 70 from the contacts R carried by the downwardly extending conducting rods S supported by the bed of the engine but insulated therefrom by the insulators T. If the shoe D leaves the rails, the springs O force the 75 shoe downwardly and contacts Q and R are brought into contact to complete a local circuit through the local battery U which may be carried in the casing H in the tender B. From one pole of the battery U the wire 2 80 leads to the magnet W and from thence the circuit continues by wire 2 to the frame of the engine at 3. From the other pole of the battery the wire 4 is connected to the conducting rods S at the points 5 and is insulated 85 from the engine frame, so that when the circuit is completed between contacts Q and R the magnet W is energized. To the plunger 90 e of the magnet is pivotally connected the movable switch arm d adapted to make contact with the contact e when the magnet W is energized, thus completing the circuit of the storage battery G through the wires 6 and 7 and the main conductors a, b.

The two parts of each coupling device E 95 and the coupling chain F are adapted to be released by means of compressed air cylinders X controlled by electrically operated valves Y, which valves may be contained in the casings Z adjacent the cylinders X and 100 serve to admit air from the compressed air train pipes f to the cylinders X.

In the casings Z are arranged electro magnets g connected by wires 8 and 9 with the line wires a and b respectively. The magnet 105 core 10 is connected to the lever 11, which is pivoted at 12 to the casing Z. This lever 11 has also pivotally connected thereto the

valve stem 13 of the valve Y. The valve stem 13 above the valve Y is provided with a coiled equalizing spring 13^a, the tension of which is adjustable through an adjusting nut 13^b, this nut being adjusted on a threaded portion provided on the valve stem. This coiled spring is proportioned to provide a pressure a little less than the normal pressure of the compressed air from the air train 10 pipe, this spring thus counteracting or nearly equalizing the air pressure on the underside of the valve, thereby allowing the magnet to open the valve. With this construction, when the line circuit a b is energized, all the magnets g are energized and the valves Y are opened, the compressed air being thus admitted through pipe f and casting Z behind the pistons h in the cylinder S, thus actuating the pistons and piston rods 20 j. The cylinders X are preferably provided with back pressure valves k controlled by springs o. The piston rods j as shown are extended and each is provided with a pin p operating in the slotted end q of an arm r connected to the rock shaft s extending transversely of the car and provided with a crank arm t connected to the chain u for releasing the coupling e. Any suitable coupling and releasing mechanism may be provided and connected to be operated by the movements of the piston rod j.

In order to release the coupling chains F suitable mechanism is provided actuated by the movement of the piston and piston rod. 35 The piston rod j is preferably squared for a portion of its length and provided with a rack v meshing with the central pinion w on the transverse shaft x. The outer ends of this shaft are provided with pinions y meshing with the vertical racks z provided with vertical movable pins 20 which hold the chain hooks 21 fast to the rods 22. The guide 23 for the pins 20 is preferably provided having rollers 24 interposed between 40 the guide and the pin, so that the pin will slide easily vertically. As the piston rod j moves outwardly the pinion w, shaft x, pinion y and pin z are moved and the pins are raised from their sockets and the chain 45 hooks 21 released.

In Fig. 5 another type of coupling is shown in which a bell crank lever 25 is hung from a support 26 and the slotted end 27 slidably connected to the pin p on the piston rod j. The other end of the bell crank lever is connected to a chain 28 for releasing the coupling. The rod 29 by which the coupling is operated passes underneath the coupling. The coupling device shown in Fig. 60 4 is more especially for freight trains, while that shown in Figs. 5 and 6 is for ordinary passenger trains, but other forms of the device may be used. As at present used the coupling release shown in Figs. 5 and 6 is

operated by hand as by means of a hand lever in place of the rod 29.

I claim and desire to obtain by Letters Patent the following:

1. In a coupling release system for railway trains, the combination of an engine 70 and car, of coupling means between the same, devices operating to uncouple the coupling means, a member supported so as to normally be in contact with a rail, and connections between the member and the uncoupling devices whereby when the member leaves the rail the uncoupling devices are caused to operate.

2. In a coupling release system for railway trains, the combination of an engine 80 and car, of coupling means between the same, devices operating to uncouple the coupling means, a member supported so as to be normally in contact with a rail, and connections including electrically controlled devices between the member and the uncoupling devices whereby the uncoupling devices are thrown into operation when the member leaves the rail.

3. In a coupling release system for railway trains, the combination with an engine 90 and cars, of coupling devices, fluid pressure means for uncoupling said devices, electrically controlled means for actuating said fluid pressure means, a normally deenergized electric circuit throughout the train controlling said electrical actuating means, and a local circuit controlled by the derailment of the engine for closing said train circuit.

4. In a safety coupling release system for railway trains, the combination with the engine and cars, of coupling devices and safety chains, fluid pressure means connected so as to release said couplings and coupling 105 chains, electrically actuated valves controlling said fluid pressure means, a main train circuit, a storage battery for energizing the same, a shoe adapted to bear upon one of the rails and connected to the engine, and means controlled by said shoe for closing the main train circuit when the engine is derailed.

5. In a coupling release system for railway trains, the combination with an engine 115 and cars, of coupling devices, compressed air cylinders and pistons therein operating to uncouple the devices, connections between the compressed air train pipe and the cylinders including electrically operated valves, 120 a normally open electric circuit controlling said valves, and a local circuit controlled by the derailment of the engine for closing the train circuit.

6. In a coupling release system for railway trains, the combination with an engine and cars, of coupling devices, a shoe carried by the engine and contacting with a rail, a

local circuit closed by the derailment of the shoe, a main train circuit normally open but closed when the local circuit is closed, and connections operated by the closing of the 5 main circuit for uncoupling the coupling devices.

In testimony whereof I have signed this

specification in the presence of two subscribing witnesses.

ARTHUR F. HETHERINGTON.
